UNITED STATES PATENT OFFICE.

JOHN F. BARNHART, OF AKRON, OHIO.

DESIGN FOR A PENHOLDER.

SPECIFICATION forming part of Design No. 35,059, dated September 10, 1901.

Application filed May 23, 1901. Serial No. 61,620. Term of patent 14 years.

To all whom it may concern:

Be it known that I, JOHN F. BARNHART, a citizen of the United States, residing at Akron, in the county of Summit and State of Ohio, have invented and produced a new and original Design for Penholders; and I do hereby declare the following to be a full, clear, and exact description of the invention, such as will enable others skilled in the art to which it applies to make and use the same.

This invention relates to a unique and novel design for a penholder, and, as illustrated, the penholder has its upper end portion gradually tapered on straight lines, its intermediate portion swelled, the opposite end portion gradually contracted, and having the penholding end outwardly flared and intersected by the convex extremity, from which a rounded projection extends centrally and has its outer end flattened.

In the accompanying facsimile drawings of the design, Figure 1 is a perspective view of a penholder embodying the design. Fig. 2 is a plan view showing more clearly the outline.

Corresponding and like parts are referred

to in both views of the drawings by the same reference characters.

The penholder is provided at its lower end with an annular enlargement 1, whose sides are outwardly diverged, said enlargement being approximately of conical form and having its base 3 convex and provided centrally with a rounded projection 4, flattened at its end. The holder is swelled, as shown at 2, and the part 5 intermediate the annular enlargement 1 and swell 2 is contracted slightly on inwardly-curved lines. The upper end portion 6 of the holder gradually tapers toward its extremity.

Having thus described the invention, what is claimed as new is—

The design for a penholder, substantially as herein shown and described.

In testimony whereof I affix my signature in presence of two witnesses.

JOHN F. BARNHART. [L. S.]

Witnesses:

C. O. KERSTETTER,
F. O. NEWCOMB.
